UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

FIBER-CASE RAILWAY-TORPEDO.

1,153,048.

Specification of Letters Patent. Patented Sept. 7, 1915.

Application filed September 17, 1913. Serial No. 790,257.

To all whom it may concern:

Be it known that I, FRANK DUTCHER, a citizen of the United States, residing at Versailles, in the county of Allegheny and State of Pennsylvania, have invented certain new and useful Improvements in Fiber-Case Railway-Torpedoes, of which the following is a specification, reference being had therein to the accompanying drawing.

10 My invention relates to improvements in fiber case railway torpedoes, made of a sheet of fiber so folded and cemented together that a strong, durable and waterproof torpedo is produced.

15 The object of my invention is to form the casing of a fiber torpedo from a blank of fiber and so fold it around the explosive tablet or compound that the same is wholly inclosed and at the same time provide means 20 whereby the lead or spring attaching strap is securely fastened thereto.

A still further object of my invention is to provide a torpedo of this character in which a flat lower face is formed to rest 25 upon the rail and at the same time provide a cheap, simple and more effective torpedo having certain details of structure herein-after more fully set forth.

Referring now to the drawings: Figure 1 is a perspective view of my improved torpedo applied to the rail and using the lead attaching strap. Fig. 2 is a perspective bottom plan view of the torpedo shown in Fig. 1. Fig. 3 is a vertical transverse sectional view taken on the line 3—3 of Fig. 1. Fig. 4 is a longitudinal sectional view taken on the line 4—4 of Fig. 3. Fig. 5 is a perspective view of the blank from which my improved torpedo is formed, showing it in a partly folded position. Fig. 6 is a bottom perspective view of a modified form of torpedo embodying my invention, showing a spring clip applied thereto. Fig. 7 is a longitudinal sectional view of Fig. 6. Fig. 8 is a top plan view of the blank of which my torpedo is formed, showing the means by which the spring clip attaching plate is secured to the blank.

Referring now to the drawing, 1 represents the blank of which my improved torpedo is formed, and consists of a main body-portion 2, having at one side the flap 3, having its ends beveled, as indicated at 4. The outer edge of the flap 3 is provided with a flap 5, which is of an area approximately equal

to that of the explosive compound 6, to be inclosed in the torpedo. The outer edge of the flap 5 is provided with a flap 7, which has its edges 8 diverging outwardly and formed on the outer end of the said flap 7 is 60 a flap 9. This flap 9 is of an area equal to that of the main-body portion 2 and fits tightly down upon the same, as will be hereinafter more fully described.

The main body portion 2 of the torpedo, 65 in the form shown in Figs. 1 to 5, is provided with two longitudinally extending spaced slits 10 and 11, through which the lead attaching strap 12 is threaded. The blank of which the torpedo is formed is preferably of fiber, such as paper, and it has been found that the ordinary paper roofing, such as is commonly used forms a very good composition out of which to stamp the blanks. Such roofing is usually flexible and enables 70 the blank to be readily folded. The ends of the body-portion 2 are provided with flaps 13 and 14, which are of a length slightly greater than the inclined walls 4 of the flap 3, the purpose of which is to allow the flaps 75 13 and 14 to assume a curved position and be folded inwardly as clearly shown in Fig. 4. In assembling the torpedo the explosive

compound or tablet 6 is placed upon the upper face of the flap 9 and folded over 80 upon the flap 5. The upper face of the body-portion is then coated with cement or other waterproofing material and the lower face of the flap 9 is folded down upon the body-portion and cemented thereto, the flaps 85 90 3 and 7 covering the sides of the explosive tablet 6. The ends of the torpedo case are then given a heavy coating of cement as indicated at 15, and the end flaps folded inwardly and upwardly under the lower face 95 of the flap 5, as clearly shown in Fig. 4 of the drawings.

In the modification shown in Figs. 6, 7 and 8, instead of providing the main-body portion 2 with the parallel longitudinal slits 10 and 11, I secure a spring clip rail attaching member 16. This member 16 is provided with four upwardly extending ears 17, which extend through openings in the body-portion and turned over as indicated at 18, 100 upon the upper face of the body-portion. The spring clip 19 is riveted to the member 16 by a rivet 20, as shown in Figs. 6 and 7.

In the form shown in Figs. 6, 7, and 8, the blank is made precisely as that shown in 110

the first five figures and needs no further description.

Having thus described my invention, what I claim and desire to secure by Letters Patent is:

1. A railway torpedo composed of a blank having a body portion, flaps carried by one side of the body portion and constructed and folded to form an open-ended case having a reduced upper face, an explosive compound within the case and said body portion having flaps at the ends of a length greater than the open ends of the case and adapted to be folded into the same in a curved position, and having their outer edges abutting the lower face of the top of the torpedo case.
2. A railway torpedo comprising a body portion, a flap secured to one side of the body portion and having slanting end walls, the said flap carrying at one side a rectangular top of an area less than the body portion, the opposite edge of said top carrying a flap having its walls diverging and a rectangular portion carried by the free edge of the last-mentioned flap and of an area equal to that of the body portion, an explosive compound within the body-portion and flaps carried by the ends of the body portion, and of a length greater than the open slanting ends of the case and adapted to be folded into the same in a curved position and having their outer edges abutting the lower face of the top of the torpedo case.
3. A railway torpedo, composed of a blank having a body-portion, flaps carried by the body-portion and constructed and arranged to be folded to form an open ended case having the upper face of a length less than that of the body-portion, an explosive compound within the case, said body-portion having flaps at the ends of a length greater than the open ends of the case and adapted to be folded into the same in a curved position, substantially as shown and described.
4. A railway torpedo composed of a blank having at one side flaps constructed and arranged to form an open ended case secured to the upper face of the body portion, an explosive compound within the open ended case and end flaps carried by the ends of the body portion and of a length greater than the end walls of the case and adapted to fold

up within the ends of the open ended case in a curved position against the side walls thereof and under the top thereof in a 55 curved position.

5. A railway torpedo composed of a blank having at one side flaps constructed and arranged to form an open ended case secured to the upper face of the body portion, a rail-attaching strap secured to the lower face of the body portion, an explosive compound within the open-ended case and end flaps carried by the ends of the body portion, and of a length greater than the end walls of the case and adapted to fold up within the ends of the open ended case in a curved position against the sides and under the top thereof in a curved position.

6. A railway torpedo comprising a body 70 portion, flaps carried by the body portion and constructed and folded to form an open ended case having a reduced upper face and an explosive compound within the case, and said body portion having flaps at the ends of 75 a length greater than the open ends of the case and adapted to be folded into the same in a curved position and having their outer edges abutting the lower face of the top of the case.

7. A railway torpedo composed of a blank having a body portion, having two slits, a rail-attaching strap threaded through said slits for securing it thereto, flaps carried by one side of the body portion and constructed 85 and folded to form an open-ended case, an explosive compound within the case, the upper face of the case being shorter than the body portion, a plastic cement composition placed within the open ends of the case 90 against the explosive mixture and said body portion having flaps at the ends of a length greater than the open ends of the case and adapted to be folded into the same in a curved position against the cement, and having 95 their outer edges abutting the lower face of the top of the open-ended case.

In testimony whereof I hereunto affix my signature in the presence of two witnesses.

FRANK DUTCHER.
